UNITED STATES PATENT OFFICE

ROY GEORGE HAWLEY, OF BRADFORD, PENNSYLVANIA

PUMP FOR OIL WELLS

Application filed June 15, 1927. Serial No. 198,882.

My invention consists in the novel features hereinafter described, reference being had to the accompanying drawings which show one embodiment of my invention selected by me for purposes of illustration, and the said invention is fully disclosed in the following description and claims.

In the operation of oil well pumps a considerable amount of sand is forced up through the barrel during the pumping operation. This sand has a greater specific gravity than the oil and tends to settle to the bottom of the tubing, between the tubing and the exterior of the barrel, and after a considerable period of operation the sand packs solidly in the space around the barrel, which makes it extremely difficult to withdraw the barrel. It is necessary to renew the cups or gaskets of the pump plunger from time to time, as they become worn, and it is also necessary to remove the sucker rods and barrel at times for the purpose of removing paraffin, and as the barrel is frequently 1000 feet or more below the surface, the sanding in of the barrel often makes it impossible to withdraw it with the sucker rods, and it is frequently necessary to pull up the tubing with the rods and extract the barrel from the tubing above ground. This often results in injury to the barrel, and in any case results in material loss of time and money. The main feature of my invention consists in providing means for preventing the accumulation of sand between the barrel and the tubing, so that the barrel can be readily withdrawn with the rods whenever this may become necessary without danger of injury to the barrel.

In carrying out my invention the upper portion of the barrel is provided with a head, having a sleeve of smaller diameter movable vertically through a collar secured to the upper end of the pump valve, said head and collar being provided with opposed annular clamping faces for engaging a laterally expandible packing ring, and said head being provided with laterally extending discharge apertures located above the packing ring, or packer, and below a partition provided with an aperture through which the pump rod only may pass, means being provided for locking

the head and collar in position to expand the packer and close off the tubing below the same, which surrounds the barrel, thus preventing any sand from working down between the tubing and the barrel. Any sand which may collect while the pump is not working, between the head and the tubing, will be driven out by the jets of oil discharged horizontally and with great force through the discharge apertures, on its way to the surface of the ground through the tubing, so that there is no possibility of the pump barrel becoming "sanded-in", or wedged in the casing, by an accumulation of sand.

My invention also includes certain novel features of construction and combination of parts hereinafter described, and particularly pointed out in the claims, whereby the packer may be compressed or released, and whereby the pump barrel together with the connected parts may be readily withdrawn from the tubing.

Referring to the accompanying drawings, Fig. 1 represents a sectional view partly in elevation showing the lower part of the well tubing, the pump barrel and pump.

Fig. 2 is a similar view showing the upper part of the pump barrel, the head and connecting collar.

Fig. 3 is an enlarged sectional view of the barrel head and attaching collar, showing the packer in position before it is laterally expanded.

Fig. 4 is a similar view showing the parts in the position which they occupy when the packer is under compression and is expanded laterally against the inner surface of the tubing.

Fig. 5 is a detail view of the upper part of the barrel head and a part carried by the pump rod and sucker rods, for turning the head to lock it in open or closed position with respect to the packer.

Referring to the drawings, 1 represents the tubing which extends down into the well from the surface of the ground, to the desired depth at which the oil is to be pumped. The lower portion of the tubing, 1, is preferably provided with a portion, 2, of reduced diameter, forming an annular seat, 3, upon

which the pump barrel is supported when in operative position. 4 represents the pump barrel, which is provided adjacent to its lower end with a shoulder, 5, to engage the seat, 3, of the tubing, below which point the barrel is preferably provided with a portion of reduced diameter, carrying the cups, 6, fitting the reduced portion, 2, of the tubing and making a tight joint therewith, below which the barrel is provided with the usual strainer, 7. The upper end of the barrel is provided with a collar, 8, having an annular clamping face, 9, at its upper end, to engage the annular packer. 10 represents the head of the barrel provided with a sleeve, 11, adapted to slide vertically in the collar, 8, and provided with an annular clamping shoulder, 12, above the shoulder, 9, of the collar, 8, an annular compressible ring packer, 13, being inserted between the shoulders, 9 and 12. This packer may be formed of any suitable material, as rubber, cork, or cork composition, leather, or lead of thin gauge. The opposing faces of the shoulders, 9 and 12, are also preferably provided with annular lips, indicated at 12^a, at their outer edges, which have a tendency to hold the packer within them so that when it is compressed vertically it will be forced outward between said lips, against the wall of the tubing, while the inner portions are firmly held in position around the sleeve, 11. The head, 10, is provided above the shoulder, 12, with a plurality of lateral discharge apertures, indicated at 14, and preferably disposed horizontally, and above said apertures the head is provided with a partition, indicated at 15, having an aperture, 16, therein, of a size to snugly fit the pump rod, or polished rod, 17, connected with the plunger, 18, of the pump. The upper end of the head is provided with a closure, 19, having a guiding aperture, 20, for the pump rod, 17, also fitting the rod snugly, and forming practically a stuffing box. The interior of the head between the closure, 19, and the partition, 15, is preferably of greater diameter than the pump rod, forming an annular space, 21, surrounding the same, and thus reducing the friction on the rod. The pump rod, 17, is provided above the closure, 19, with a top piece, or connection, 22, having a threaded aperture, 23, in its bottom, into which the upper end of the pump rod is threaded, the said top piece being provided with a threaded stem, 24, adapted to be connected to the lower sucker rod section, 25, as shown in the drawing. The upper end of the head and the top piece, 22, are provided with interlocking portions, to permit the head of the pump barrel to be rotated from the top of the well, when desired, by turning the sucker rods. In this instance the top piece, 22, is shown provided on opposite sides with lugs, 26, adapted to engage recesses, 27, in the upper part of the

closure, 19, as best seen in Fig. 5. I also provide means for locking the head, 10, and the collar, 8, in the open position in which the packer is not compressed, and in the closed position in which the packer is compressed vertically and expanded laterally. In this instance I have shown the sleeve, 11, of the head provided with a stud, 28, which may be a heavy screw projecting therefrom and engaging a bayonet slot in the collar 8 indicated as a whole at 29, and comprising a lower horizontal locking portion, indicated at 30, a central vertical portion indicated at 31, and an upper horizontal locking portion, indicated at 32.

The pump barrel is provided at its lower end with the usual standing valve, or bottom valve, 33, engaging a seat, 33^a, and the lower end of the pump rod, 17, is provided with a valve casing, 34, carrying the plunger valve, or traveling valve, indicated at 35. The plunger is also provided with a plurality of cups, or gaskets, indicated at 36, tightly fitting the barrel, an oil passage, indicated at 37, being provided through the plunger to the valve seat, 35^a, of the valve, 35. The valves are shown as being in the form of ball valves, each provided with a suitable cage. Any preferred form of valves may be employed, however, as the particular construction of the valves forms no part of my present invention.

The lower end of the sleeve, 11, forming part of the head, 10, preferably extends below the lower end of the collar, 8, and is provided with a lifting collar, indicated at 38. When the packer is in its natural position and is not under compression, this collar, 38, which is threaded on the lower end of the sleeve, 11, engages the lower end of the collar, 8, as shown in Fig. 3, so that in lowering the barrel into the well, the pin, 28, may be relieved of undue strain. I prefer, however, to so construct the parts that the strain will be divided between the collar, 38, and the pin, 28, so that both may be relied upon in lowering or lifting the pump barrel.

In lowering the barrel into the well a sucker rod section is screwed on to the stem, 24, of the top piece, 22, and the barrel and sucker rod are lowered into the tubing, 1. Additional sections of the sucker rod are connected and the barrel lowered until the shoulder, 5, comes to rest upon the seat, 3, at the bottom of the tube, as indicated in Fig. 1. When lowering the barrel into the well, it will be understood that the packer is in the condition shown in Fig. 3, that is to say, is not compressed vertically. As soon as the lower end of the barrel is seated, a suitable wrench is applied to the upper end of the uppermost sucker rod section and the sucker rods are turned in a direction to move the pin, 28, along the horizontal portion, 32, of the locking slot, 29, so as to bring the pin into

vertical alignment with the vertical portion, 31 of the slot, the interlocking projections, 26 and recesses, 27, of the top piece, 22, and the head, 10, (or closure, 19, thereof) permit the head to be turned with the sucker rods, thereby carrying the pin laterally in the slot, 29, as stated. As soon as the pin has been brought into alignment with the vertical portion, 31, of the slot, 29, the head, 10, will move downward under the weight of the sucker rods, compressing the packer, 13, vertically and expanding it horizontally into contact with the inner surface of the tubing, 1, as indicated in Fig. 4. The sucker rods are then rotated still further, so as to carry the pin, 28, into the horizontal section, 30, of the slot, 29, thus locking the parts in their adjusted position. The sucker rod may now be lifted sufficiently to permit of the desired stroke of the pump plunger and connect it to the pumping means, which may be of any desired character, to effect the pumping of the well. It will be understood that on the up stroke of the plunger, the traveling valve, 35, will remain seated, and the suction of the plunger will draw the oil from below the pump barrel into the pump barrel through the valve seat, 35^a, thereby lifting the valve, 33. On the down stroke of the plunger the valve, 33, seats, and the oil within the barrel passes up through the valve seat, 35^a, lifting the traveling valve, 35, the oil continuing to pass up as the plunger reciprocates, until it reaches the partition, 15, of the head, 10, where it is forced laterally in jets against the inner surface of the tubing immediately above the packer, and thence upward through the narrow channel between the head and the tubing, and then between the sucker rods and the tubing, to the surface of the ground where it is conducted to any desired point by suitable pipe connections. It will be seen that no sand can collect between the pump barrel and the tubing under any circumstances whatsoever, as no oil can pass below the packer, 13. Any sand which may tend to collect between the upper portion of the head above the packer and the tubing, will be dislodged by the jets of oil discharged laterally through the apertures, 14, and carried upward with the oil. The oil passes through the holes, 14, at considerable pressure and at greater velocity than it passes upward through the pump barrel, or through the tubing, as the holes, 14, are of relatively smaller diameter, so that the jets of oil will clear away any sand which tends to collect above the packer, at every stroke of the pump, keeping the oil agitated and carrying the sand out with the oil. It follows, therefore, that the barrel cannot become wedged in the tubing, and may be readily drawn out when it is desired, as for the removal of paraffin from the sucker rods, or for the removal and replacement of any of the cups,

or gaskets, of the pump plunger, or for any other purpose.

To remove the barrel, the sucker rods are detached from the pumping apparatus and lowered, and at the same time rotated by a suitable wrench until the interlocking parts, as the projections, 26, and recesses, 27, of the top piece and head are brought into engagement. The sucker rods are then turned in a direction to bring the locking pin, or stud, 28, into alignment with the vertical portion, 31, of the slot, 29, when the sucker rods may be raised, thereby drawing up the pump rod, 17, until the plunger strikes the collar, 38, and lifts the sleeve, 11, and head, 10, so as to bring the collar, 38, into engagement with the lower end of the collar of the pump barrel, and as herein shown the stud, or pin, 28, against the upper edge of the slot, 29. The upward movement of the head, 10, will release the packer, and the further upward movement of the sucker rods will draw the pump barrel entirely from the well, the several sections of the sucker rod being unscrewed as the lifting of the pump barrel proceeds, in the usual manner. The packer may, on being freed, resume its original position if sufficiently elastic, or it may break up as the barrel is withdrawn from the well, but the expense of replacing the single packer, which is the only part liable to injury in the removal of the barrel, is comparatively inexpensive, and the difficulty of removing a "sanded-in" barrel with the expense and trouble and possible destruction of the barrel, are entirely eliminated.

What I claim and desire to secure by Letters Patent is:—

1. In a pump for oil wells, the combination of a barrel provided with a plunger and pump valves, a pump rod connected with said plunger, said barrel having its upper portion provided with horizontally disposed discharge apertures, an annular compressible packer carried wholly by and surrounding the barrel immediately below said discharge apertures and having a released diameter substantially less than the interior diameter of the surrounding tube or casing, whereby the barrel may be passed into the well to any depth without bringing the packer into contact with the tube, means for retaining the packer in uncompressed condition while the barrel is being lowered into the well and means for releasing said retaining means and forcing said packer laterally into contact with the surrounding tube to prevent deposit of sand between the barrel and tube below said discharge apertures.

2. In a pump for oil wells, the combination of a barrel provided with a plunger and pump valves, and a pump rod connected with said plunger, said barrel having its upper portion provided with horizontally disposed discharge apertures, discharging against the

inner face of the enclosing tube, an annular packer carried wholly by and surrounding the barrel immediately below said discharge apertures, and means for forcing said packer into contact with the surrounding tube, whereby the deposit of sand between the barrel and tube below said discharge apertures is prevented, and the discharge of the oil pumped through said discharge apertures will prevent the accumulation of sand above said apertures.

3. In a pump for oil wells, the combination of a barrel, a plunger therein and pump valves, and a pump rod connected with the plunger, said barrel being provided adjacent to its upper end with a horizontal partition having an aperture fitting the pump rod, said barrel having laterally disposed discharge apertures below said partition, an annular

20 packer carried wholly by and surrounding the barrel immediately below the discharge apertures, and means for forcing the packer into contact with the surrounding tube, whereby the deposit of sand around the barrel below the packer is prevented, and the oil pumped is forced laterally through said discharge apertures immediately above the packer, to prevent the accumulation of sand around the barrel above the packer.

30 4. In an oil pump, the combination of a barrel provided at its upper end with a head movable vertically with respect to the barrel, and providing an annular recess between a portion of said head and a part rigidly connected with the barrel, a compressible packer located in said recess, said head being provided immediately above the packer with horizontally disposed discharge apertures communicating with the interior of the barrel, whereby the packer may be compressed vertically and expanded laterally into contact with the surrounding tube by a longitudinal movement of the head with respect to the barrel, and means for locking the head with respect to the barrel to hold the packer under compression.

50 5. In an oil pump, the combination of a barrel provided at its upper end with a head movable vertically with respect to the barrel, and providing an annular recess between a portion of said head and a part rigidly connected with the barrel, a compressible packer located in said recess, said head being provided immediately above the packer with horizontally disposed discharge apertures communicating with the interior of the barrel, whereby the packer may be compressed vertically and expanded laterally into contact with the surrounding tube by a longitudinal movement of the head with respect to the barrel, means for locking the head with respect to the barrel with the packer in normal uncompressed position and also with the packer in compressed position.

65 6. In an oil pump, the combination of a

barrel provided at its upper end with a head movable vertically with respect to the barrel, and providing an annular recess between a portion of said head and a part rigidly connected with the barrel, a compressible packer located in said recess, said head being provided immediately above the packer with horizontally disposed discharge apertures communicating with the interior of the barrel, whereby the packer may be compressed vertically and expanded laterally into contact with the surrounding tube by a longitudinal movement of the head with respect to the barrel, and locking means for locking the head with respect to the barrel, comprising a locking stud on one of said parts and a locking slot in the other of said parts, having vertical and horizontal portions to engage said stud.

7. In a pump for oil wells, the combination of a barrel provided with a plunger and valves, and a pump rod connected with the plunger, said barrel being provided with a head movable vertically with respect to the barrel and a hollow sleeve extending within a portion rigidly connected with the barrel, an annular recess being provided between the head and a part rigidly connected with the barrel and surrounding said sleeve, an annular packer in said recess, the said head being provided above the packer with laterally disposed discharge apertures communicating with the interior of the valve, said sleeve and the part connected with the barrel and surrounding the sleeve being provided the one with a locking stud and the other with a locking slot having vertical and horizontal portions, a part connected with the pump rod and provided with portions to interlock with portions of said head, to enable said head to be rotated to move said stud into and out of engagement with the horizontal portions of the locking slot.

8. In a pump for oil wells, the combination of a barrel provided with a plunger and valves, and a pump rod connected with the plunger, said barrel being provided with a head movable vertically with respect to the barrel and a hollow sleeve extending within a portion rigidly connected with the barrel, an annular recess being provided between the head and a part rigidly connected with the barrel and surrounding said sleeve, an annular packer in said recess, the said head being provided above the packer with laterally disposed discharge apertures communicating with the interior of the valve, said sleeve and the part connected with the barrel and surrounding the sleeve being provided the one with a locking stud and the other with a locking slot having vertical and horizontal portions, a part connected with the pump rod and provided with portions to interlock with portions of said head, to enable said head to be rotated to move said

stud into and out of engagement with the horizontal portions of the locking slot, and a lifting collar on the sleeve connected with said head, for engaging the part rigidly connected with the barrel to relieve the locking stud from undue strain in inserting and removing the barrel.

9. In a pump for oil wells, the combination of a barrel provided with a plunger and 10 valves, and a pump rod connected with the plunger, said barrel being provided with a head movable vertically with respect to the barrel and a hollow sleeve extending within a portion rigidly connected with the barrel, 15 an annular recess being provided between the head and a part rigidly connected with the barrel and surrounding said sleeve, an annular packer in said recess, the said head being provided above the packer with laterally disposed discharge apertures communicating with the interior of the valve, said sleeve and the part connected with the barrel and surrounding the sleeve being provided the one with a locking stud and the 20 other with a locking slot having vertical and horizontal portions, a part connected with the pump rod and provided with portions to interlock with portions of said head, to enable said head to be rotated to move said stud into and out of engagement with the horizontal portions of the locking slot, and a lifting collar on the lower end of said sleeve for engaging the part rigidly connected with the barrel, said sleeve being constructed to 25 engage the plunger when the latter is raised to its fullest extent to remove the barrel from the well.

10. In a pump for oil wells, the combination of a barrel provided adjacent to its 40 lower end with a reduced portion forming a shoulder to engage a seat in the well tube and support the barrel therein, said reduced portion being provided with means for fitting the interior of the tube and making a 45 tight joint therewith, said barrel being provided with a plunger and pump valves and a pump rod connected with the plunger, a collar rigidly secured to the upper end of the barrel and forming a part thereof, a 50 head provided with a downwardly extending sleeve of reduced diameter fitting within said collar, and provided with a lifting collar below the same, a packer surrounding said sleeve and located between the barrel collar 55 and said head, a locking stud on said sleeve, a locking slot in said barrel collar having horizontal and vertical portions for engaging said stud and locking the head with respect to the barrel with the packer in normal 60 and also in compressed position, said head being provided above said packer with a partition having an aperture therein fitting the pump rod, and with horizontally disposed radial discharge apertures located between 65 said partition and the packer and communi-

cating with the interior of the barrel, a top piece connected with the pump rod and provided with means for attaching it to the sucker rods, said top piece and said head being provided with interlocking portions to permit said head to be rotated by the sucker rods, the said plunger being constructed to engage the lower end of said sleeve when lifted to its highest position in the barrel, to raise the head with respect to the barrel and to enable the barrel to be suspended from the sucker rods in lowering the barrel into the well and removing it therefrom.

In testimony whereof I affix my signature. 80
ROY GEORGE HAWLEY.
